(57) **CLAIM**

The ornamental design for a transverse portion of a container, as shown and described.

DESCRIPTION

FIG. 1 is a front elevational view of a container according to our new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The dash-dash-dash-type broken lines shown in the drawings are included for the purpose of illustrating environmental structure and form no part of the claimed design. The dot-dash-dot-dash-dot-dash type broken lines shown in the drawings define the boundaries of the claimed design.
